(57) CLAIM

The ornamental design for a graphical user interface, as shown and described.

DESCRIPTION

FIG. 1 is a front view of a graphical user interface for a display screen of a communications terminal;

FIG. 2 is a front view of a second embodiment thereof; and,

FIG. 3 is a front view of a third embodiment thereof.

The broken line drawings of text and the display screen in all views is for illustrative purposes only and forms no part of the claimed design.

1 Claim, 3 Drawing Sheets
